Inventor

Stephen Smith

UNITED STATES PATENT OFFICE

STEPHEN SMITH, OF PHILADELPHIA, PENNSYLVANIA, ASSIGNOR TO THE HORNER BROTHERS, OF SAME PLACE.

DESIGN FOR A CARPET.

SPECIFICATION forming part of Design No. 12,784, dated February 21, 1882.

Application filed January 11, 1882. Term of patent 3½ years.

To all whom it may concern:

Be it known that I, STEPHEN SMITH, of the city of Philadelphia, county of Philadelphia,
State of Pennsylvania, have invented and produced a new and original Design for Carpets,
of which the following is a specification.

The nature of my design is fully represented in the accompanying photographic illustration, to which reference is made.

I claim as my invention—

The design for a carpet, as shown.

Witnesses: STEPHEN SMITH.

JOHN T. THOMPSON,
THOMAS ONSLOW.
